UNITED STATES PATENT OFFICE.

ALPHEUS O. HURXTHAL, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA.

DESIGN FOR A TOASTER.

Application filed February 15, 1928. Serial No. 25,444. Term of patent 14 years.

To all whom it may concern:

Be it known that I, ALPHEUS O. HURXTHAL, a citizen of the United States, residing in Philadelphia, Pennsylvania, have invented a Toaster, of which the following is a specification, reference being had to the accompanying

drawing, in which the figure is a perspective view of a toaster illustrating my design.

I claim:

The ornamental design for a toaster, substantially as shown.

ALPHEUS O. HURXTHAL.
